UNITED STATES PATENT OFFICE

ALLEN EVERET HALL, OF NEWPORT NEWS, VIRGINIA

DESIGN FOR A MOTOR VEHICLE DIRECTION INDICATOR SIGNAL

Application filed March 22, 1932. Serial No. 43,262. Term of patent 14 years.

To all whom it may concern:

Be it known that I, ALLEN EVERET HALL, a citizen of the United States, residing at Newport News, in the county of Warwick and State of Virginia, have invented a certain new, original, and ornamental Design for a Motor Vehicle Direction Indicator Signal, of which the following is a specification, reference being had to the accompanying drawing, forming a part thereof.

Figure 1 is a perspective view of the device seen from the front, and

Figure 2 is a perspective view of the device seen from the rear.

I claim:

The ornamental design for a motor vehicle direction indicator signal as shown.

ALLEN EVERET HALL.
